UNITED STATES PATENT OFFICE.

SUSIE MATILDA HOPPER, OF HAYS, KANSAS.

QUILT-FASTENER.

1,277,725.

Specification of Letters Patent.

Patented Sept. 3, 1918.

Application filed May 16, 1918. Serial No. 234,968.

To all whom it may concern:

Be it known that I, SUSIE M. HOPPER, a citizen of the United States, and a resident of Hays, in the county of Ellis and State of Kansas, have invented certain new and useful Improvements in Quilt-Fasteners, of which the following is a specification.

My invention is an improvement in quilt fasteners, and has for its object to provide mechanism of the character specified for holding a quilt in the quilting frame without the necessity of sewing the quilt to the frame.

In the drawings:

Figure 1 is a perspective view of a portion of the frame, with the quilt in place;

Fig. 2 is a section on the line 2—2 of Fig. 1, looking in the direction of the arrows adjacent to the line;

Fig. 3 is a perspective view of one of the clamps.

In the present embodiment of the invention the quilting frame 1 has secured thereto at regular intervals and at the proper distances from each other yoke shaped brackets, each consisting of a body 2 and arms 3, the arms being right angular in form. Preferably, these supports are secured to the frame by means of screws 4, and a clamping plate, consisting of portions 5 and 6 extending at an obtuse angle with respect to each other, is journaled between the arms of each bracket.

Each of these clamping plates, as shown, has longitudinally extending journal pins 7 at its ends and at the junction of the portions 5 and 6, and these pins are journaled in openings in the arms of the bracket. The

free edge of the portion 6 is provided with teeth, as shown, and these teeth are adapted to engage the quilt 8. A plate 9 of metal or the like is secured to the under face of the quilting frame, the said plate extending far enough inside the frame to form a support for the edge of the quilt, the quilt edge being clamped between the plate and the teeth of the plate 5—6.

In use, the edge of the quilt is inserted between the plates 5—6 and 9 when the portions 5 of the plates 5—6 are swung upwardly. This releases the portions 6, moving them substantially parallel with the plate 9. The edge of the quilt is then inserted, and the plates 5—6 are swung downwardly into the position of Fig. 2. The quilt is then held firmly clamped in the frame while at the same time it may be easily released.

I claim:

In combination with a quilting frame, of plates secured to the under surface of the frame and extending inwardly beyond the frame, the edges of the quilt being adapted to rest upon these plates, a series of yoke shaped brackets secured to the inner face of the quilt frame, each bracket comprising a body secured to the frame and inwardly extending arms, and a clamping plate journaled in the arms and coöperating with the first named plate to grip the quilt, said clamping plate consisting of two portions extending at an angle with respect to each other, one of the said portions having teeth and engaging the quilt, the other serving as a handle for swinging the plate.

SUSIE MATILDA HOPPER.
